Assistant Examiner—Lavone D. Tabor

(73) Assignee: Koninklijke Philips Electronics, N.V.,
Eindhoven (NL)

(57) CLAIM

() Term: 14 Years

The ornamental design for a storage case for an electric toothbrush, as shown and described.

(21) Appl. No.: 29/220,231

DESCRIPTION

(22) Filed: Dec. 28, 2004

FIG. 1 is a perspective view showing our design;

(51) LOC (8) Cl. 04-99

FIG. 2 is a front view thereof;

(52) U.S. Cl. D4/199

FIG. 3 is a rear view thereof;

(58) Field of Classification Search D4/199;

FIG. 4 is a left side view thereof;

D3/201, 205; D9/414, 424-426, 430, 432;

FIG. 5 is a right view thereof;

206/349, 361, 362.1, 362.2, 368, 369, 461,

FIG. 6 is a top view thereof;

206/463, 470, 471, 823; 220/4.21, 4.22, 4.23,

FIG. 7 is a bottom view thereof;

220/4.24

FIG. 8 is a perspective view of our design in open position;

See application file for complete search history.

FIG. 9 is a front view of our design in open position;
